US00D782316S

(12) United States Design Patent (10) Patent No.: US D782,316 S
(45) Date of Patent: * Mar. 28, 2017

(54) JAR

(71) Applicant: SOREMARTEC S.A., Findel (LU)

(72) Inventor: Giuseppe Terrasi, Benevello (IT)

(73) Assignee: Soremartec S.A., Findel (LU)

() Term: 15 Years

(21) Appl. No.: 29/533,623

(22) Filed: Jul. 20, 2015

(30) Foreign Application Priority Data

Jan. 22, 2015 (WO) 867717501

(51) LOC (10) Cl. 09-01

(52) U.S. Cl.

USPC D9/522

(58) Field of Classification Search
